SEAL ASSEMBLY

Madden T. Works, Houston, Tex., assignor to
 Cameron Iron Works, Houston, Tex., a corporation of Texas

Application August 22, 1947, Serial No. 770,011

8 Claims. (Cl. 285—22)

1

This invention relates to seal assemblies and particularly to seal assemblies which may be employed in connection with casing heads, casing and other equipment employed at the tops of wells. The general object of this invention is to provide an improved seal assembly of the type referred to which will not occupy substantially more room than the conventional type of casing head or tubing head and which will provide a seal between such casing or tubing head and a pipe passing therethrough, as well as suspend such pipe.

It is a more specific object of this invention to provide a relatively simple, compact, inexpensive seal assembly of the type referred to in which the formation of a seal between the pipe hanger and the well head will be assisted by the weight of the pipe suspended on the pipe hanger.

Another object of this invention is to provide a seal assembly of the type referred to in which the pipe hanger has separate means for suspending the pipe and for forming a seal about the pipe.

Another object of this invention is to provide a seal assembly of the type referred to in which separate seals are provided between the pipe hanger and the pipe to be suspended therein and between the pipe hanger and the well head, and in which sufficient pressure to actuate such seals may be applied simultaneously from the exterior of the assembly.

Another object of this invention is to provide a seal assembly of the type referred to in which a seal is provided between the pipe hanger and a pipe passing therethrough and in which additional pressure may be applied to such seal to render it more effective by means accessible from the exterior of the assembly.

Other objects and advantages of this invention will become apparent from the following description and the accompanying drawing wherein is shown by way of illustration and example but not by way of limitation, one embodiment of this invention.

In the drawing:

The single figure is a view partly in side elevation and partly in vertical cross section showing a seal assembly constructed in accordance with this invention, secured to the upper end of a well surface casing and surrounding and forming a seal about a well casing, and having secured to its upper end a bonnet or other fitting forming a part of the usual Christmas tree assembly of a well.

Referring now more in detail to the drawings, the casing head 1 is secured by means of threads

2

or other suitable connection to the upper end of a surface casing 3 of a well. Extending upwardly through the casing head 1 is a well casing 4 and secured to the upper end of the casing head 1 by means of studs 5 or the like is the flange 6 of a bonnet or other equipment to be employed above the casing head. This flange 6 is sealed to the flange 7 at the upper end of the casing head by means of a conventional metal seal ring 8.

10 It will be understood that while the parts 1, 3 and 4 have been referred to as a casing head, a surface casing and a well casing, this invention is not limited to such application but the element 1 on a smaller scale might serve as a tubing head in which event the pipe 3 would represent a well casing and the pipe 4 a well tubing. The term well head is employed in this specification and the appended claims as a generic designation including casing heads and tubing heads.

20 The well head which is illustrated as having the usual side flow openings 9 and as having an interior surface including an upper zone 10 and a lower zone 11, both of which are substantially cylindrical, and an upwardly facing shoulder 12 between and joining such cylindrical zones.

25 At one point of its circumference the flange 7 is provided with a bore 13 leading from its outermost surface and provided with a threaded plug 14. This bore 13 is of such a diameter that it

30 may be said to provide a reservoir for a purpose presently to be set forth. Leading from its inner end so as to connect this reservoir with the interior of the well head at a point a suitable distance above the shoulder 12 is a passage 15 of a 35 diameter somewhat smaller than the diameter of the reservoir 13.

Positioned within the well head 1 between it and the pipe 4 is a hanger member 16 which is of annular form. This hanger member 16 is 40 adapted to fit within the well head 1 and has external substantially cylindrical surfaces 17 and 18 which are of such diameter as to provide sliding fits respectively within the internal cylindrical surfaces 10 and 11 of the well head. These 45 cylindrical surfaces 17 and 18 are joined by a downwardly facing shoulder 19 which, when the hanger member 16 is within the well head 1, will be opposed to and spaced from the shoulder 12 within the well head. This obviously provides

50 an intermediate zone between the well head and the hanger in which these two parts are spaced from each other to provide an annular chamber. Two annular sealing members 21 and 22, respectively, are located within this chamber adjacent its upper and lower ends and preferably in engage-

ment with the shoulders 19 and 12. In between these two annular sealing members is a skeleton type spacer ring 23 whereby downward force which may be applied for example to the sealing member 21 may be transmitted to the sealing member 22, and whereby a space is created and maintained between these two sealing members which space is capable of receiving and containing a flowable pressure applying material by which the sealing members may, if desired, be forced into tighter sealing engagement with the hanger and well head, respectively. It is to be noted that the passage 15 in the well head is so located that when the hanger is in its normal position as illustrated in the drawing, the inner end of this passage 15 will open into the space provided by the spacer ring 23.

The hanger 16 is also provided on its inner surface with an inwardly opening groove 24 in which is located a distortable annular sealing member 25, and the hanger is provided with a passage 26 extending from the space provided by the spacer ring 23 into the bottom of the groove 24. It will be seen that filling the reservoir 13 with a material which is flowable under pressure and then by inserting the plug 14 into the outer end of this reservoir and tightening the same, the material flowable under pressure will be forced from the reservoir 13 through the passage 15 and into the space provided by the spacer ring 23. Thence it will be made to flow through the passage 26 and into the groove 24 behind the sealing member 25. Further tightening of the plug 14 will cause a hydraulic pressure to be applied to each of the sealing rings 21, 22 and 25 in a direction to urge them into tighter sealing engagement so that even after the device has been assembled the sealing engagement provided by each of the three sealing rings may be intensified by merely tightening of the plug 14. Thus, any leaks which might appear between the well head 1 and the hanger 16 or between the hanger 16 and the pipe 4 may be stopped by the application of additional pressure.

The hanger 16 is also provided below the groove 24 with a slip receiving groove or bowl having a tapered surface 27 adapted to receive slips 28 for engagement with the pipe 4 to suspend the same. It will be readily seen that weight suspended by these slips will be transmitted to the hanger 16 pulling downwardly on this hanger and providing for the application of sealing pressure to the sealing members 21 and 22 entirely without regard to the application of fluid pressure to these rings through the tightening of the plug 14.

In the practice of this invention it will be understood that the well head 1, if the same be a casing head, will be first mounted upon the surface casing 3. Then when it is desired to run the well casing and suspend and seal the same in the well, the well casing 4 will be lowered into the well and cemented in place in the usual manner. Thereupon the hanger 16 will be placed over the upper end of the casing with the slips 28 in place therein and with the seal rings 21, 22 and 25 and the spacer ring 23 in the proper positions as indicated. The proper amount of strain will be placed on the well casing and then released whereupon the weight of the casing and the strain thereon will be transmitted through the slips 28 to the hanger 16. This will tend to move the hanger 16 downwardly and through the co-action of the shoulders 19 and 12 and of the spacer ring 23 will place pressure upon the seal-

ing members 21 and 22 forcing them into tight sealing engagement with the hanger and well head.

The upper end of the well casing will then be cut off at an appropriate level as indicated and the bonnet or other equipment placed on top of the well head and secured thereto by means such as the studs 5.

The plug 14 will then be removed and the reservoir 13 filled with a plastic or flowable material such as heavy grease with asbestos fibers therein, whereupon the plug will be replaced and tightened, forcing this material under pressure through the passages 15 and 26 so that it will act upon sealing rings 21, 22 and 25. This will not only urge the sealing rings 21 and 22 more tightly into sealing engagement with the well head and hanger but will move the seal ring 25 into sealing engagement about the well casing 4, preventing leakage along the outside of the well casing through the hanger.

From the foregoing it will be seen that by the structure illustrated and described there has been provided a device which is capable of carrying out and accomplishing all of the objects and advantages sought by this invention.

Having described my invention, I claim:

1. In combination, an annular well head having on its inner surface upper and lower cylindrical zones joined by an upwardly facing shoulder, an annular hanger having on its outer surface upper and lower cylindrical zones of diameters to fit within said zones in the well head respectively and joined by a downwardly facing shoulder, said hanger having an inwardly open groove in its inner surface, a pair of annular distortable sealing members between said shoulders, a skeleton type spacer ring between said sealing members, an annular distortable sealing member in said groove, said hanger and head having communicating passages therein connecting the exterior of said head with the space between said first two sealing members and with the bottom of said groove, and means for forcing a flowable material under pressure through said passage and into the space between said first mentioned distortable sealing member and into said groove behind the distortable sealing member therein.

2. In combination, an annular well head having on its inner surface upper and lower cylindrical zones joined by an upwardly facing shoulder, an annular hanger having on its outer surface upper and lower cylindrical zones of diameters to fit within said zones in the well head respectively and joined by a downwardly facing shoulder, said hanger having an inwardly open groove in its inner surface, a pair of annular distortable sealing members between said shoulders, a skeleton type spacer ring between said sealing members, an annular distortable sealing member in said groove, said well head having a reservoir formed in one side thereof and said head and hanger having registering passages therein connecting said reservoir with the space between said first two sealing members and with the bottom of said groove, and means for forcing a flowable material under pressure through said passages and into the space between said first mentioned distortable member and into said groove behind the distortable sealing member therein.

3. In combination, an annular well head having on its inner surface upper and lower cylindrical zones joined by an upwardly facing shoulder, an annular hanger having on its outer surface upper and lower cylindrical zones of diam-

eters to fit within said zones in the well head respectively and joined by a downwardly facing shoulder, said hanger having an inwardly open groove in its inner surface, a pair of annular distortable sealing members between said shoulders, a skeleton type spacer ring between said sealing members, an annular distortable sealing member in said groove, said well head and hanger having passages therein providing communication between the exterior of said head and the space between said first two sealing members and with the bottom of said groove, means for forcing a flowable material under pressure through said passages and into the space between said first mentioned distortable sealing members and into said groove behind the distortable sealing member therein, and pipe suspending means carried by said hanger for suspending a pipe therein.

4. In combination, an interfitting annular well head and annular hanger having intermediate registering zones with adjacent surfaces of different diameters to provide an annular space between them, a pair of annular distortable sealing members in said space adjacent the opposite ends thereof respectively, said hanger having an inwardly opening groove in its inner surface, a third annular distortable sealing member therein, and means for forcing a flowable material under pressure into the groove behind said third sealing member.

5. In combination, an interfitting annular well head and annular hanger having intermediate registering zones with adjacent surfaces of different diameters to provide an annular space between them, a pair of annular distortable sealing members in said space adjacent the opposite ends thereof respectively, said hanger having an inwardly opening groove in its inner surface, a third annular distortable sealing means therein, and means for forcing a flowable material under pressure between said first mentioned sealing members and into the groove behind said third sealing member.

6. A pipe hanger comprising an annular member having its inner surface formed with an annular inwardly opening packing receiving groove and an annular inwardly opening slip receiving groove, the bottom of slip receiving groove being tapered, and having its outer surface formed with upper and lower substantially cylindrical zones and a downwardly facing shoulder between them.

7. In combination, a well head, a hanger located therein, spaced distortable sealing members between said head and hanger, said hanger having a groove in its inner surface, a distortable sealing member in said groove, and a common means for supplying flowable material under pressure to all three of said distortable sealing members to move them toward sealing position.

8. A pipe hanger comprising an annular member having its inner surface formed with an annular inwardly opening packing receiving groove and an annular inwardly opening slip receiving groove, the bottom of slip receiving groove being tapered, and having its outer surface formed with upper and lower substantially cylindrical zones and a downwardly facing shoulder between them and a passage formed in the annular member communicating between the packing receiving groove and the outer periphery of the member at the smallest diameter of one of the cylindrical zones.
